KARL C. RANDALL, OF EDGEWOOD PARK, AND CHARLES B. GIBSON, OF WILKINSBURG, PENNSYLVANIA, ASSIGNORS TO WESTINGHOUSE ELECTRIC AND MANUFACTURING COMPANY, A CORPORATION OF PENNSYLVANIA.

SEPARATING APPARATUS FOR LIQUIDS.

1,024,598.

Specification of Letters Patent. Patented Apr. 30, 1912.

Application filed July 13, 1910. Serial No. 571,785.

To all whom it may concern:

Be it known that we, KARL C. RANDALL and CHARLES B. GIBSON, both citizens of the United States, and residents, respectively, of Edgewood Park and Wilkinsburg, both in the county of Allegheny and State of Pennsylvania, have invented a new and useful Improvement in Separating Apparatus for Liquids, of which the following is a specification.

Our invention relates to separating apparatus for liquids and it has special reference to apparatus for separating non-miscible liquids.

The object of our invention is to provide an apparatus of the above indicated class that shall be simple and durable in construction and efficient in operation.

Considerable difficulty has been experienced in the past with the formation and accumulation of water in transformer oil, and our invention embodies an inexpensive and effective means for drawing off such accumulated water as it is formed and thus avoiding the disastrous effects which might otherwise be produced.

According to our invention, we make use of a substance or material which, when saturated with moisture, is practically impervious to oil but allows a comparatively free passage of water. The physical properties of plaster of Paris render it of special value in this particular connection, although other substances having similar properties, may be employed, if desired.

Those skilled in the art will readily understand that our invention is not restricted to specific structural details, materials or liquids, as the apparatus of our invention, broadly considered, may be employed to separate a variety of non-miscible liquids and may be constructed of a variety of materials.

Without attempting to illustrate the various forms and uses of our apparatus, we will proceed to describe a specific embodiment of the principle of our invention as applied to a common type of electrical transformer, for the purpose of removing water from the insulating oil.

The single figure of the accompanying drawing, is a view, partially in elevation

and partially in vertical section, of a transformer tank equipped with a separating apparatus constructed in accordance with our invention.

Referring to the drawing in detail, a separating apparatus 1, which is connected to a transformer tank 2, near its bottom, by suitable pipe fittings 3, comprises an inner casting 4, having a projecting portion 5 at one end, to which the pipe fitting 3 is secured, an outer casting 6 which is screwed upon said inner casting, a disk 7 of plaster of Paris disposed between said outer and inner castings, and a tube 8 which is adapted to be filled with water.

The inner casting 4 is substantially cylindrical in shape and its outer surface is provided with screw threads 9. The outer end 70 of said casting is provided with a recess 10, the outer portion of which is adapted to receive the plaster of Paris disk 7 and the inner portion of which forms a compartment or well 11 which communicates with the 75 pipe fitting 3 by a passage 12.

The outer casting 6 is substantially of the form of a hollow cylinder with one end closed and its inner cylindrical surface is provided with screw threads 13 which 80 co-operate with the screw threads 9 on the inner casting 4. The outer casting 6 also embodies a compartment or well 14, an opening 15 into which the tube 8 is fitted and a drip cock 15^a which is adapted to 85 drain the tube 8, if desired.

The plaster of Paris disk 7, which is contained within a metallic ring 16, is fitted tightly into the outer portion of the recess 10 and the respective sides of said disk are 90 provided with felt washers 17 and 18^a.

Experiment has determined that a disk of plaster of Paris, when saturated with water, is impervious to oil and it is therefore evident that said disk must be maintained in a saturated condition, the tube 8 being provided and filled with water for this purpose. The tube 8, which fits tightly into the opening 15 and communicates with the well 14, extends upwardly in contact 100 with the transformer tank to a height substantially 83% of the normal oil level in the tank. The upper portion 18 of the tube 8 is bent over to form an inverted U and the

extremity 19 is slightly turned away from the transformer tank. A clip 20 partially surrounds the tube 8 and is held in position by means of a wire 21 which surrounds the tank.

In order to adapt the separator for commercial service, it is necessary that the disk 7 be saturated with moisture and that the well 14 and tube 8 be filled with water. Moreover, for actual operation, it is essential that sufficient water shall be contained in the bottom of tank 2 to cover the opening in the pipe connection 3, and also to fill said pipe connection, the passage 12 and the well 11 of inner casting 4. The oil level within the transformer tank is then adjusted until the water in the tube 8 is on the point of overflowing. Equilibrium is then established and, although the height of the column of water in tube 8 is less than the height of the oil in the transformer tank, a balance between the columns is maintained by reason of the differences in specific gravity of water and oil. Assuming conditions to be as indicated, the operation of the system is as follows: Such water as may be introduced into or concentrated in the transformer oil, immediately settles to the bottom, on account of its greater specific gravity, and the consequent increase in the oil level, tends to overbalance the column of water in the tube 8. The excess of water in the tank is therefore forced through the plaster of Paris disk 7, until equilibrium is reestablished, thereby causing a portion of the water in the tube 8 to be displaced. This operation continues automatically as long as moisture becomes concentrated in the oil at a sufficient rate to maintain the tube full of water. If, however, this condition is not maintained, the column of water in the tube is gradually lowered, by evaporation, until the disk 7 is no longer saturated with water. In this condition, the disk of plaster of Paris is not impervious to oil and, on account of the unbalanced pressure and the unsaturated state of the disk, oil from the tank is forced through it and is discharged from the tube until the oil level in the tube and in the tank become equalized. The action of the device as an automatic water separator is therefore destroyed. It is evident then that the separator is not adapted for use except with transformers in which water is deposited from the oil in considerable quantities and at a more or less uniform rate.

In cases where the rate of deposit of water is insufficient to maintain automatic operation, the upper end of the tube 8 may be closed and the drip cock 15^a may be employed from time to time, to drain off the excess of accumulated water. It will be observed that the drip cock 15^a is located at the top of the well 11 so that the disk 7 is

always maintained in a saturated condition to perform its function.

It will, of course, be understood that the apparatus, herein shown and described, is only illustrative of a particular means for accomplishing a specific purpose, and that details and materials of construction, and the arrangement and location of parts, may be materially varied from what is herein set forth, without departing from the spirit and scope of our invention.

We claim as our invention:

1. The combination with a receptacle for electrical apparatus and insulating liquid, of means for withdrawing water from said receptacle comprising a hollow body provided with a filtering partition, means for connecting the chamber at one side of the partition to the interior of the receptacle near its bottom, and a water-filled pipe projecting from the other chamber approximately to the surface of the liquid in the receptacle.

2. The combination with a receptacle for electrical apparatus and a body of insulating liquid, of a hollow body in open communication with the bottom of said receptacle, and having a partition which, in a state of saturation, is impervious to said insulating liquid but is pervious to water, and means for maintaining said partition in a saturated condition.

3. The combination with a tank for electrical apparatus and insulating liquid, of a hollow body communicating with an opening near the bottom of said tank, a body of porous material in said hollow body that is pervious to water but, when saturated therewith, is impervious to said insulating liquid, and means for maintaining said material in a saturated condition.

4. The combination with a tank containing two immiscible liquids of different specific gravities, of a separating device communicating with the bottom of said tank and comprising a hollow body, a partition of porous material therein, said material having the property, when saturated with the liquid of greater specific gravity, of being pervious to that liquid but impervious to the other of said liquids, and a stand-pipe for the heavier liquid.

5. The combination with a tank for electrical apparatus and insulating liquid, of means for withdrawing water from the bottom of said tank comprising a two-part hollow body, the inner part of which is connected to the tank near its bottom and the outer part of which is adapted to fit tightly over said inner part, a partition of porous material disposed between said outer and inner parts to form inner and outer chambers and composed of a material which, when saturated with water, is pervious thereto but is impervious to said insulating

20

liquid, and a stand-pipe projecting upwardly from said outer chamber to a predetermined height and filled with water.

6. The combination with a tank for electrical apparatus and insulating liquid having an outlet near its bottom, a body of porous material disposed within said outlet, means for disposing of the liquid which passes through said porous body, and means for equalizing the pressures upon the sides of said body, under normal conditions.

7. The combination with an oil-containing receptacle, of a separator for removing water from the oil in said receptacle comprising an inner cylindrical member having a recess at one end, an outer member adapted to be screwed upon said inner member, a disk of porous material seated in said re-

cess, and means for maintaining said disk saturated with water.

8. The combination with a receptacle for two nonmiscible liquids of different specific gravities, of a separating means connected to the bottom of said receptacle for removing the heavier liquid and comprising a body of filtering material and means for maintaining saturation of said material by the heavier liquid.

In testimony whereof, we have hereunto subscribed our names this 27th day of June 30 1910.
